(57) **CLAIM**

What is claimed is the ornamental design for a nestable pig figurine, as shown and described.

DESCRIPTION

FIG. 1 is a perspective view of a nestable pig figurine, showing the new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a perspective view of a nestable set of the nestable pig figurines; and,

FIG. 9 is a cross-sectional view thereof in a nested configuration, taken generally along lines 9—9 of FIG. 4, a smallest pig figurine shown complete for clarity of illustration.
